UNITED STATES PATENT OFFICE

FREDERICK B. ROSENBERGER, OF BELMONT, AND RAYMOND I. REYNOLDS, OF SOMERVILLE, MASSACHUSETTS

DESIGN FOR A BAROMETER DIAL

Application filed October 7, 1931. Serial No. 41,341. Term of patent 14 years.

To all whom it may concern:

Be it known that we, FREDERICK B. ROSENBERGER, a citizen of the United States, and a resident of Belmont, in the county of Middlesex and State of Massachusetts, and RAYMOND I. REYNOLDS, a citizen of the United States, and a resident of Somerville, in the county of Middlesex and State of Massachusetts, have invented a new, original, and ornamental Design for a Barometer Dial, of which the following is a specification, reference being had to the accompanying drawing, forming part thereof.

Referring to the drawing:

The figure is a face view of a barometer dial showing our new design.

We claim:

The ornamental design for a barometer dial, substantially as shown.

In witness whereof, we hereunto subscribe our names this sixth day of October, 1931.

FREDERICK B. ROSENBERGER.
RAYMOND I. REYNOLDS.
